DESIGN FOR A FAUCET CONNECTION

Samuel L. Weiss, Brooklyn, N. Y.

Application May 25, 1938, Serial No. 77,375

Term of patent 14 years

To all whom it may concern:

Be it known that I, Samuel L. Weiss, a citizen of the United States, residing in Brooklyn, county of Kings, and State of New York, have invented a new, original, and ornamental Design for a Faucet Connection, of which the following is a specification, reference being had to the accompanying drawing, forming part thereof.

The figure is a perspective view of the faucet connection showing my new design.

The other side is like the side shown.

I claim:

The ornamental design for a faucet connection as shown and described.

SAMUEL L. WEISS.
